UNITED STATES PATENT OFFICE

EDMUND SCHULTE, OF BRONXVILLE, NEW YORK

DESIGN FOR A BALUSTRADE UNIT

Application filed July 27, 1929. Serial No. 32,228. Term of patent 3½ years.

To all whom it may concern:

Be it known that I, EDMUND SCHULTE, a citizen of the United States, residing at Bronxville, in the county of Westchester and State of New York, have invented a new, original, and ornamental Design for a Balustrade Unit, of which the following is a specification, reference being had to the accompanying drawing, forming part thereof.

The drawing illustrates a fragmentary front elevation of a balustrade, showing my new design which is repeated on the opposite side, and one complete repeat being indicated by the dotted lines.

I claim:

The ornamental design for a balustrade unit, as shown and described.

EDMUND SCHULTE.
